UNITED STATES PATENT OFFICE.

ALTON B. CARTY, OF WASHINGTON, DISTRICT OF COLUMBIA.

PRINTER'S QUOIN.

1,335,480.

Specification of Letters Patent. Patented Mar. 30, 1920.

Application filed March 6, 1919. Serial No. 281,042.

To all whom it may concern:

Be it known that I, ALTON B. CARTY, a citizen of the United States, residing at Washington, in the District of Columbia, have invented certain new and useful Improvement in Printers' Quoins, of which the following is a specification.

My invention relates to improvements in printers' quoins of the Hempel type which are used in pairs, and more especially to one of the quoins.

My invention relates further to locking means wherein said quoins are positively locked against loosening when in position in the furniture, and, further, to means whereby said quoins are held against separation, one from the other, in case of loosening when the locking means is not employed.

My invention has for its object the use of a cotter pin of standard construction as a key or locking pin thus reducing the cost of manufacturing a specially designed pin and facilitating ready replacement by users in case of loss.

A further object of my invention consists in the ability to expand the adjacent portions of the cotter pin and thereby increasing its locking properties in use.

A further object of my invention consists in the ease with which the cotter pin may be inserted or extracted from the quoins, the head of the cotter pin being always visible in the locked quoins.

A further object of my invention consists in the provision of a locking pin receiving recess extending transversely of the head of the quoins and adapted to embrace the locking pin throughout its entire extremity, all as will be hereinafter more fully described and claimed.

Figure 1 is a plan view of one form of my improved quoins.

Fig. 2 is a cross section on line 2—2 of Fig. 1, showing bifurcated locking pin inserted.

Fig. 3 is a cross section on line 3—3 of Fig. 2, showing distortion of the bifurcated locking pin insuring positive locking of the elements.

Fig. 4 is a perspective view of one of the quoins showing the pair of upturned retaining shoulders.

Fig. 5 is a key used to impart longitudinal movement of the quoins in locking the quoins in the furniture.

Printers' quoins of the Hempel type are

most commonly used by virtue of the economy arising from the fact that the two coöperating elements are duplicates and interchangeable. By this construction it is also possible to reverse them in position. This type of quoins is effective to permit an adjustment through a wide range and to meet the ordinary requirements of a flat printing press. It is, however, a common occurrence for the frequent and periodic vibrations and jars to which such presses are subjected for these coöperating elements to shift their relative positions and to permit a loosening of the grip on the adjoining press parts. Where presses carry a body of type through an arc of movement out of the horizontal plane, this in itself gives rise to the dislodgment of any locking means which may be used to hold the elements in proper position and which locking means may have become, in the slightest degree, loose.

Applicant's device serves the purpose of holding in adjusted position the elements of a printer's quoins regardless of vibration to which the apparatus may be subjected, and regardless of movement which would serve to dislodge an ordinary locking means.

It is the object of my invention to obviate all these objections and provide a quoins that will be simple in construction and thoroughly reliable in operation.

The quoins are designated by the numerals 10 and 11, each being provided with the usual racks 12 and 13, between which the pinion of the key 14 is introduced for expanding or contracting the quoins elements by a partial turn in one direction or the other. The inclined faces of the quoins elements are each formed with centrally disposed rib members 15 and 16, the adjacent faces of which are formed with a series of corresponding semicircular notches or apertures in which a locking pin, to be described later, is adapted to be inserted. To keep the quoins elements evenly poised, one on the other during use, the usual head portions 17 and 18 are formed on one end of each quoins element. Each of the head portions is provided with a transverse elongated aperture 19 corresponding to one of the series of segmental notches in the centrally disposed inclined rib through which the locking pin 20 is adapted to pass and in which the expanded end or type 23 of the pin 20 is adapted to be held against rotation during locking of the quoins elements. The locking pin 20 is preferably of the cot-

ter pin construction, being formed of resilient metal and providing two adjacent semicircular portions 21 and 22, joined at one end in an expanded loop or end 23. A pair 5 of shoulders 24 and 25 extend at right angles to the centrally disposed inclined ribs 15 and 16 at the outer extremity of each quoin element against which the head of the corresponding element is adapted to im- 10 pinge.

The operation of the quoin is as follows: The quoin elements are placed, one on the other, as in the Hempel quoin, and by engagement and rotation of the pinion of the 15 key 14 between the racks 12 and 13, are contracted one on the other and wedged tightly in the furniture. The locking pin 20 is then inserted in either of the elongated 20 apertures 19 and a corresponding and regis- 25 tering semicircular notch in the centrally disposed rib of the adjacent quoin element, the expanded head portion 23 of the pin 20 closely fitting the aperture 19, thus preventing rotation thereof during longitudinal 30 displacement of the quoin elements, and each of the quoin elements embracing portions 21 and 22 of the pin 20 between their adjacent and registering notched faces. The quoin elements are then expanded 35 slightly by the oscillation of the pinion of the key 14 between the racks 12 and 13 in the opposite direction, thus causing transverse separation or deflection of the portions 21 and 22 of the locking pin 20 and preventing withdrawal or loosening of the pin until 40 the pinion of the key 14 is again inserted between the racks 12 and 13, and the corresponding notched portions of the quoin elements returned to registering position.

It will be evident from the relation of the aperture 19 and the coöperating rib 16 that the cotter pin forms a locking member in which the grip is continuous throughout the greater part of the cotter pin and the 45 distortional effect has been localized between the two members 21 and 22 of the cotter pin. As shown in Fig. 2 the cotter pin is in continuous engagement with the member 11 from the extremity of the member 22 to 50 the bight portion 20. The walls of the aperture 19 serve at their innermost juncture to closely grip the cotter pin. The bight by reason of the swelling portion is also gripped between the sides of the aperture 19. In this 55 way rotational movement of the bight around the member 22 is prevented. The outer portion of the side walls of the aperture 19, however, permits the member 21 to be drawn out of line from the member 22. In this way the member 21 may be said 60 to have a radial motion around member 22 as a fulcrum and the entire distortional effect becomes localized in the free member 21.

During adjustment of the quoin in the 65 furniture and also in case the locking pin 20

is not used through inadvertence, a pair of shoulders 24 and 25 are provided extending at right angles to the centrally disposed inclined ribs 15 and 16 at the outer extremity of each of said quoin elements against which the head of the corresponding quoin element is adapted to impinge, and serves to limit the backing-off or separation of the quoin elements one from the other in case of loosening, while in an expanded position 70 in the furniture. Each of the shoulders 24 and 25 are formed with inclined faces which are of such angles as will permit of the passage of the adjacent quoin element when pressure is applied by the action of the 80 pinion of the key 14 between the racks 12 and 13 in either direction, all as will be readily understood.

Having described my invention in full, what I claim as new and desire to cover by 85 Letters Patent is:

1. A printer's quoin comprising a pair of quoin elements, the combination of a bifurcated locking pin, said locking pin adapted to extend transversely between the adjacent 90 faces of said elements and adapted to be distorted by longitudinal displacement of said elements.

2. In combination with a printer's quoin, locking means comprising a transversely 95 distortable pin and means on said quoin for preventing rotation of said pin.

3. In combination with a pair of quoin elements formed with corresponding notches in their adjacent faces, a bifurcated pin 100 adapted to extend transversely therethrough and be distorted by longitudinal displacement of said elements.

4. A printer's quoin comprising a wedge-shaped member formed with a centrally disposed rib and a head at one end thereof, and a pair of upturned shoulders having sloping side faces arranged one on either side of said centrally disposed rib adjacent the opposite end of said member. 110

5. In a printer's quoin, the combination of a pair of quoin elements, each comprising a wedge-shaped member formed with a central longitudinal rib, an upstanding head at one end, and a pair of transverse shoulders at the other end, said shoulders having sloping side faces. 115

6. In a printer's quoin, the combination of a pair of quoin elements, each provided with a centrally disposed rib portion and a head adjacent one end thereof, said rib portions provided with notches in their adjacent faces and said head portions provided with an elongated aperture adapted to register with a notch of the opposing rib, and a locking pin adapted to be inserted in said elongated aperture and the registering notch. 120

In testimony whereof I affix my signature.

ALTON B. CARTY.
